BALL HANDLING MECHANISM

George A. Montooth, Long Beach, Calif., assignor to The Brunswick-Balke-Collender Company, a corporation of Delaware

Application November 24, 1954, Serial No. 471,012

7 Claims. (Cl. 273—49)

This invention relates to ball elevating mechanism and more particularly to a rotating ball elevator for use with an automatic pinsetter.

An object of this invention is to provide a new and improved ball elevating mechanism.

Another object of this invention is to provide a new and improved ball elevating mechanism wherein the balls are elevated by a ring-type rotating elevator.

A further object of the invention is to provide a ball elevating mechanism including a rotating annular member and a pair of vertically arcuate tracks having generally horizontal lower ends mounted within the periphery of the annular member whereby the annular member engages the underside of a ball and elevates it along the tracks to a discharge track.

Another object of the invention is to provide a ring-type rotating ball elevator extending across the alley pit for engaging a bowling ball and, in association with vertically arcuate tracks disposed within the periphery of the ball elevator, elevating the ball to a discharge track.

Another object of the invention is to provide ball elevating mechanism in the form of a pair of vertically-disposed, spaced-apart, arcuately-shaped track members which are spaced from a ring-shaped or annular ball elevating member a distance slightly less than the diameter of a bowling ball and are positioned within the periphery of the ball elevating member, one of said track members being disposed forwardly of the elevating member and the other track member being disposed rearwardly of the elevating member, the lower end of the track member disposed forwardly of the ball elevator being pivotally mounted in order to move vertically as a ball moves thereunder and to then return downwardly to a position wherein the ball is confined between the pair of track members and rests on the ball elevating member and may be elevated by the rotating ball elevating member.

The objects of the invention generally set forth, together with other ancillary advantages, are attained by the construction and arrangement shown by way of illustration in the accompanying drawing, in which:

Fig. 1 is a perspective view in elevation of the ball and pin elevating mechanism as mounted in a bowling alley;

Fig. 2 is a perspective view in elevation of the mechanism shown in Fig. 1 with the ball elevating mechanism removed;

Fig. 3 is a fragmentary perspective view in elevation of the mechanism shown in Fig. 2 and particularly the mechanism for resetting the pin-engaging paddle members;

Fig. 4 is a vertical view in section of one of the pin-engaging paddle members showing the latch mechanism for holding the paddle member in its extended pin-engaging position; and,

Fig. 5 is a diagrammatic end view in elevation of the ball elevating mechanism showing a ball engaged between the annular ball-elevating member and the spaced-apart track members looking toward the mechanism from the left-hand end of Fig. 1.

While this invention is susceptible of embodiment in

2

many different forms, there is shown in the drawings and will herein be described in detail an illustrative embodiment of the invention with the understanding that the present disclosure is to be considered as an exemplification of the principles of the invention and is not intended to limit the invention to the embodiment illustrated. The scope of the invention will be pointed out in the appended claims.

My improved pin and ball elevating mechanism may be mounted at the rear of a pit having side walls one of which is indicated at 1 and a pit floor formed of a plurality of moving belts 2, 3 and 4. Reference may be had to my co-pending application, Serial No. 2205, filed January 14, 1948, now Patent No. 2,729,449, granted January 3, 1956, for a complete disclosure as to the construction and drive for these belts. The belts 2 and 4 are moved in a manner whereby their upper reaches move toward the middle belt 3, the upper reach of which moves toward the rear of the pit. Thus, it will be seen that pins and a ball will be directed to the rear of the pit at a point or position approximately mid-way between the sides thereof.

As shown in Figs. 1 and 2, a vertically-disposed framework is formed from one set of connected channel members 5, 6, 7, 8, 9 and 10 which are interconnected with another set of connected channel members 11, 12, 13, 14, 15 and 16, the two sets of channel members being reinforced by cross members such as 17 and 18 and being interconnected by channel members 19, 20, 21 and 22. Rotatably mounted within the framework is a ball elevating mechanism which is in the form of a rotatably mounted ring-shaped or annular member 25 and a pair of cooperating arcuately-shaped, spaced-apart track members 26 and 27 which are vertically disposed and spaced apart from the annular member 25 a distance slightly less than the diameter of a bowling ball A.

The annular member 25 is driven by a belt 30 disposed about the outer periphery of the annular member and passing over a driving pulley 31. Guide rollers 32, 33, 34, and 35 mounted in the supporting framework function to guide the annular member 25 for rotation and also to guide belt 30 on the periphery of the annular member. A weighted roller 36 is mounted on pivotal arms, one of them being shown at 37 and functions to maintain the belt 30 taut.

A ball trap mechanism is provided to insure that a ball will be properly engaged by the track members 26 and 27 so as to ensure proper alignment of the ball with the annular member 25. This mechanism takes the form of pivotally mounting the lower end 38 of the track member 27 by means of a bracket 39 secured to a support block 40 for the lower track end 38 and a hinge member 41 connected to a central frame member 42. It will thus be seen that the lowermost position of the annular member 25 is adjacent the conveyor 3 which constitutes a ball pickup position. As a ball is moved onto the annular member 25, it will cause slight upward movement of the lower track end 38 to permit movement of the ball into engagement with the lower end 26a of the track member 26. As this occurs, the lower end 38 will lower slightly and the ball will be rolled up the track members 26 and 27 by clockwise rotation of the annular member 25 as shown in Fig. 1. A plurality of wires indicated generally at 45 secured to brackets 46, 47, 48 and 49 form a side guide to prevent accidental movement of a ball rearwardly of the track member 26. The upper ends of the track members 26 and 27 terminate in wires 50, 51 and 52 which form a discharge track for receiving a ball and guiding it to a conventional return track, not shown.

The track member 27 is disposed forwardly of the ball advancing member 25 while the track member 26 is disposed rearwardly of the ball advancing member 25.

so that contact of the annular member 25 with the ball A is at a point between the points made by contact of the ball with the track members 26 and 27, this being shown diagrammatically in Fig. 5. Positive elevation of the ball is assured because the weight of the ball aids in holding the ball in driving engagement with the annular member 25 when the ball first enters the elevator.

The pin elevating mechanism more clearly shown in Fig. 2 is in the form of an annular member 60 disposed around the central frame member 42. Annular member 60 is rotated by a belt 61 (Fig. 3) disposed around a portion of the periphery of the annular member 60. The belt is driven by a driving pulley 62. The annular member 60 is guided by a plurality of guide rollers 63, 64, 65 and 66 mounted in the framework. The guide rollers 64, 65 and 66 also function to guide the belt 61. As shown in the lower left-hand corner of Fig. 2, the belt 61 leaves the periphery of the annular member 60 at that point and travels over an idler pulley 70.

As shown more clearly in Fig. 3, the annular member 60 is provided with a rim made up of rim parts 71 and 72. The rim 72 is of a slightly greater diameter than rim 71 so that a pair of outer flanges 73 and 74 on the guide roller 66 and also on guide rollers 63, 64 and 65 engage the edges of rim 72 and guide the annular member 60 while a pair of inner flanges 75 and 76 on these guide rollers ride on the rim 72 and engage the edges of the belt 61 to guide the belt.

The rim 71 is recessed at peripherally-spaced points as is the associated adjacent area of the body of the annular member 60 to receive pin engaging paddles or paddle members 77.

As shown in Figs. 2, 3 and 4, the paddle members 77, all of which are identical, are pivotally mounted on brackets 80 secured to the inner side of the rim portion 72. Inasmuch as each of the paddle members are identical, only one will be described in detail.

Each bracket 80 has ears 81 and 82 between which a pin 83 extends upon which the paddle member 77 is pivotally mounted. A spring 84 connected between the bracket 80 and the paddle member 77 urges the paddle member to a position wherein it extends radially of the annular member 60 for a purpose hereinafter more fully set forth. The paddle member 77 is held in a position wherein it extends parallel to the axis of the annular member 60 and against the action of the spring 84 by an L-shaped latch member 85 which has an end 86 in engagement with a notch 87 in the inner end of the paddle member 77. The latch member 85 is pivotally mounted on a bracket 88 and is urged into latching position by a spring 89 connected between the latch member and the mounting bracket 80.

As pins are directed to the rear of the pit by the pit floor belt 3, they engage the ball elevating member 25 which tends to disperse grouped pins and align the pins with their axes extending in the direction of pin travel. The pins pass beyond the ball advancing annular member 25 and into a pin guiding channel formed by a plurality of wires 90, 91, 92 and 93 which are mounted on a plurality of brackets 94, 95, 96, 97, 98 and 99. The wires form the curved pin guiding channel having a lowermost position adjacent the pit floor slightly below the lowermost position of the ball elevating member 25. The channel extends upwardly from this position and terminates at a position approximately level with the axis of the annular member 60 where the pins are discharged one by one into a pair of vertically-disposed belts 100 and 101 (Fig. 1) which pass around a pair of lower pulleys 102 and 103, respectively. The belt 101 extends vertically and passes around a driving roller 104 while the belt 100 passes around a pulley 105 and changes from a vertical to a horizontal direction, the left hand end of the belt 100 passing around a driving pulley 106. Thus, a pin entering in the pin guiding channel formed by the

wires 90-93 will be moved along the channel by a pin engaging paddle 77 until the pin passes between the belts 100 and 101. The pin will then be elevated by the belts and directed out onto the horizontal stretch of belt 100. It is necessary to prevent interference between a paddle member 77 and the belt 100 as the paddle member is carried up between the belts 100 and 101 so that a trip block 117 (Fig. 4) is mounted on the frame-work adjacent the lower end of the belts 100 and 101 for tripping the latch member 85 to permit the paddle member 77 to move to its radial position as shown in Fig. 3. The trip block 117 is carried by a stationary portion of the framework and is positioned so as to permit the paddle members 77 to effectively position succeeding pins between the belts 100 and 101, and to trip the latches 85 so that the paddle members move past the belts without conflict therewith. As the annular member 60 continues to rotate, the radially-extended paddle member 77 will contact the bent cocking wire 110 and be reset in its normal pin engaging position, as shown in Fig. 3.

Although the specific mechanism forms no part of this invention, the drive belts for the annular members 25 and 60 as well as the pin engaging belts may be driven by a motor 111 which through belts 112 drives a pulley 113 which has a sprocket 114 connected therewith. The sprocket drives the driving pulley 31 for the belt 30 which drives the ball elevating member 25. A sprocket 115 on the same shaft as the driving pulley 31 drives a sprocket 116 by means of a chain 118 for driving the drive pulley 104 for the pin engaging belt 101. The drive pulley 113 has a shaft 120 which may be interconnected by mechanism not shown to a shaft 121 upon which the driving pulley 106 for the belt 100 is mounted. The end of the shaft 121 has a chain and sprocket drive 122 leading to a sprocket 123 (Fig. 3) which drives the pulley 62 for the belt 61 which drives the annular pin advancing member 60.

The ball and pin separating apparatus disclosed herein is claimed in my copending divisional application Serial No. 639,698, filed February 12, 1957.

I claim:

1. A ball elevating mechanism for use with a bowling alley having a pit provided with mechanism therein for directing balls to a ball pickup position at the rear of the pit and approximately mid-way between the sides thereof, comprising, in combination, a vertically disposed supporting framework extending across the rear of the pit; an annular ball elevating member vertically disposed in said framework and having its lower extremity adjacent the ball pickup position, means including a driven belt disposed around the periphery of the annular member for imparting rotation thereto, guide rollers mounted in said framework and in engagement with said annular member and belt for guiding the annular member and belt for rotation in a fixed path, means disposed within the periphery of the annular member for guiding and holding a bowling ball against the annular member as a ball is elevated thereby including a pair of vertically disposed spaced apart track members arcuately shaped to correspond to the curvature of the annular member and spaced from the ball elevator a distance less than the diameter of a bowling ball, the lower ends of said track members being substantially horizontal and terminating in a position above the ball pickup position, one of the ball track members being disposed forwardly of the annular member and the other being disposed to the rear of the annular member, and means mounting the lower end of the forwardly disposed ball track member for vertical movement so that the lower end of said ball track member may be raised as a ball moves into engagement therewith to permit movement of a ball slightly therebeyond and then may return to its initial position so that a ball will be guided between said spaced apart track members and engaged

thereby in order to insure alignment of the ball with the annular member and elevation thereby.

2. A ball elevating mechanism for use with a bowling alley having a pit provided with a mechanism therein for directing balls to a ball pickup position comprising, in combination, a vertically-disposed supporting framework, an annular ball elevating member vertically disposed in said framework and having its lower extremity adjacent the ball pickup position, means including a driven belt disposed around the periphery of the annular member for imparting rotation thereto, guide rollers mounted in said framework and in engagement with said annular member and belt for guiding the annular member and belt for rotation in a fixed path, means disposed within the periphery of the annular member for guiding and holding a bowling ball against the annular member as a ball is elevated thereby including a pair of vertically disposed spaced apart track members shaped to correspond to the curvature of the annular member and spaced from the ball elevator a distance slightly less than the diameter of a bowling ball, the lower ends of said track members being substantially horizontal and terminating in a position above the ball pickup position, one of the ball track members being disposed forwardly of the annular member and the other being disposed to the rear of the annular member, and means mounting the lower end of the forwardly disposed ball track member for vertical movement so that the lower end of said ball track member may be raised as a ball moves into engagement therewith to permit movement of a ball therebeyond and then may return to its initial position so that a ball will be guided between said spaced apart track members and engaged thereby in order to insure alignment of the ball with the annular member and elevation thereby.

3. A ball elevating mechanism for use with a bowling alley having a pit provided with a mechanism therein for directing balls to a ball pickup position at the rear of the pit and approximately mid-way between the sides thereof, comprising, in combination, a vertically-disposed supporting framework extending across the rear of the pit, a ring-shaped ball elevating member vertically disposed in said framework and having its lower extremity adjacent the ball pickup position, means for rotating the ball elevating member in a fixed path, and means for guiding and holding a bowling ball against the inner surface of the ball elevating member as a ball is elevated thereby including a pair of spaced apart track members shaped to correspond to the curvature of the ball elevating member and spaced from the ball elevator a distance less than the diameter of a bowling ball, the lower ends of said track members being substantially horizontal and terminating in a position above the ball pickup position, one of the ball track members being disposed forwardly of the ball elevating member and the other being disposed to the rear of the ball elevating member, and means movably mounting the lower end of the forwardly disposed track member to permit entry of a ball into position between the track members and the elevating member to trap the ball therebetween for elevation thereby.

4. A ball elevating mechanism for use with a bowling alley having a pit and a ball pickup position in the pit comprising, in combination, a vertically-disposed supporting framework, a ring-shaped ball elevating member vertically disposed in said framework and having its lower extremity adjacent the ball pickup position, means for rotating the ball elevating member in a fixed path, and means for guiding and holding a bowling ball against the inner surface of the ball elevating member as a ball is elevated thereby including a pair of spaced apart track members arcuately shaped to correspond to the curvature

of the ball elevating member and spaced from the ball elevator a distance slightly less than the diameter of a bowling ball, one of the ball track members being disposed forwardly of the ball elevating member and the other being disposed to the rear of the ball elevating member and means mounting the lower end of the forwardly disposed track member to admit a ball into position between the track members and the elevating member to be rolled up the track members by the elevating member.

5. A ball handling mechanism for use with a bowling alley having a pit and a ball pickup position in the pit comprising, in combination, a ring-shaped ball elevating member disposed in a vertical plane and having an uninterrupted ball engaging inner surface with its lower extremity positioned adjacent the ball pickup position, means for supporting and rotating the ball elevating member in said vertical plane, means for directing a ball onto the inner surface of the ball elevating member at the pickup position so that the ball is supported by the elevating member at the pickup position, and arcuately shaped ball track means disposed within the periphery of the elevating member for guiding and holding a bowling ball against the inner surface of the ball elevating member to be rolled up the track means by the elevating member.

6. A ball elevating mechanism for use with a bowling alley having a pit and a ball pickup position comprising, in combination, a ball elevating member extending transversely of the alley pit and having an exposed uninterrupted radially inner surface movable continuously through an arcuate path having a lower generally horizontal portion at the ball pickup position and an upper portion adjacent a ball discharge position; means for moving the ball elevating member through said arcuate path, means for directing a ball onto said inner surface of the ball elevating member at the ball pickup position so that the ball is initially supported by the ball elevating member, and guide means for guiding and holding a bowling ball against the radially inner surface of the ball elevating member to be rolled up the guide means by the elevating member from the ball pickup position to the ball discharge position.

7. For use with a bowling alley having means in the alley pit for directing balls centrally and rearwardly toward a ball pickup position, a ball elevating mechanism, comprising, in combination, a vertically disposed, ring-shaped ball elevating member extending transversely of the pit and having a continuous ball engaging inner surface with its lower extremity positioned at the ball pickup position so that balls are directed thereonto and supported thereby, means for supporting and rotating the ball elevating member, and guide means disposed within the periphery of the ball elevating member and spaced therefrom to prevent passage of the ball rearwardly and for guiding and holding a bowling ball against the inner surface of the ball elevating member to be rolled up the guide means by the elevating member to a ball discharge position.
